(57) **CLAIM**

We claim the ornamental design for the electrode patch array, as shown and described.

DESCRIPTION

FIG. 1 is a top view of an electrode patch array showing our new design;

FIG. 2 is a bottom view thereof;

FIG. 3 is a side view thereof;

FIG. 4 is another side view thereof that opposes the side view of FIG. 3;

FIG. 5 is a side view thereof;

FIG. 6 is another side view thereof that opposes the side view of FIG. 5;

FIG. 7 is a top perspective view thereof; and,

FIG. 8 is a bottom perspective view thereof.

The broken lines are included for purpose of illustrating portions of the electrode patch array that form no part of the claimed design.
